UNITED STATES PATENT OFFICE

96,876

DESIGN FOR A MAGAZINE HOLDER

Ferdinand Wendl, Long Island City, N. Y.

Application June 10, 1935, Serial No. 57,206

Term of patent 7 years

To all whom it may concern:

Be it known that I, Ferdinand Wendl, a citizen of the United States, residing at Long Island City, county of Queens, Borough of Queens, and State of New York, have invented a new, original, and ornamental Design for a Magazine Holder, of which the following is a specification, reference being had to the accompanying drawing, forming a part thereof.

The figure is a perspective view of a magazine holder showing my new design.

I claim:

The ornamental design for a magazine holder as shown.

FERDINAND WENDL.
